(57) **CLAIM**

The ornamental design for an industrial computer, as shown and described.

DESCRIPTION

FIG. 1 is a top view of an industrial computer showing the new design;

FIG. 2 is a bottom view thereof;

FIG. 3 is a front view thereof;

FIG. 4 is a rear view thereof;

FIG. 5 is a right side view thereof;

FIG. 6 is a left side view thereof; and,

FIG. 7 is a bottom right perspective view thereof.

The broken line portions of the figure drawings are included to show unclaimed subject matter only and form no part of the claimed design.

1 Claim, 5 Drawing Sheets
